INTERCHANGEABLE SIGN

Charles J. Wamser, Milwaukee, Wis.

Application November 8, 1937, Serial No. 173,411

4 Claims. (Cl. 40—140)

This invention pertains to interchangeable signs, and more particularly to electrically illuminated signs provided with translucent glass panels and changeable silhouette letters disposed 5 thereon.

In signs of the foregoing type now on the market, serious difficulties have been encountered in obtaining access to the illuminating compartment, and also in the removal and cleaning 10 of the glass panels. Further, such signs are so constructed as to accumulate rain, snow, and ice, with the result that prolonged dripping occurs, which is particularly objectionable in signs or marquees supported over sidewalks or thoroughfares.

The present invention has primarily for its object to overcome the foregoing objections by the provision of an exceedingly simple and attractive illuminated changeable silhouette letter sign, in which access can be quickly had to the 20 illuminating compartment without removal of the translucent panels or silhouette letters, and which materially facilitates installation or removal of the translucent panels, for either cleaning or replacement, as well as eliminating the accumulation of water, snow, and ice.

Incidental to the foregoing, a more specific object of the present invention resides in the provision of a frame hinged to the sign housing 30 for supporting a translucent panel and changeable silhouette letters, both being readily installed or removed without resort to fastening devices.

With the above and other objects in view, 35 which will appear as the description proceeds, the invention resides in the novel construction, combination, and arrangement of parts, substantially as hereinafter described, and more particularly defined by the appended claims, it being understood that such changes in the precise embodiment of the herein disclosed invention may be made as come within the scope of the 40 claims.

In the accompanying drawings is illustrated 45 one complete example of the physical embodiment of the present invention constructed according to the best mode so far devised for the practical application of the principles thereof.

In the drawings: 50 Figure 1 is a fragmentary front elevation of a sign constructed in accordance with one form of the present invention.

Figure 2 is an enlarged transverse section 55 taken on the line 2—2 of Figure 1.

Figure 3 is a detailed fragmentary section taken on the line 3—3 of Figure 2.

Figure 4 is a perspective view of the hinged panel and letter-supporting frame.

Figure 5 is a fragmentary detail section 5 through a frame hinge, as indicated by the line 5—5 of Figure 4.

Figure 6 is a fragmentary detail section of the hinged frame taken on the line 6—6 of Figure 4; and

Figure 7 is an elevation of one of the detachable silhouette letters employed.

Referring now more particularly to the accompanying drawings, the numeral 1 designates a display housing consisting of upper and lower 15 sections 2 and 3, respectively, secured to a rear panel 4 to form an illuminating compartment 5, in which conventional light sockets 6 are mounted for reception of incandescent lamps 7. At the same time it is to be understood that other forms 20 of electric illumination may be employed without departing from the principles of the invention.

The bottom wall 8 of the upper section 2, which is of a hollow box construction, is provided with a longitudinally elevated portion 9 terminating adjacent its front edge to form a depending lip 10, which extends over the top edge of a panel 11, provided with rearwardly projecting ears 12, pivotally connected to arcuate brackets 13 secured to the lower wall 25 30 of the top section 2, inwardly of the lip 10.

Like the upper section 2 the lower section 3 of the housing 1 is also of box formation, the top wall 14 of which is inclined outwardly and downwardly intermediate its front and rear edges, and has formed thereon adjacent its outer edge a longitudinal, vertical lip 15, against which the bottom edge of the hinged frame 11 abuts. From the lip 15 the wall 14 is also beveled downwardly and outwardly to form a water shed. 35

Considering now in detail the hinged frame 11, the same comprises spaced vertical bars 16 connected at their upper and lower ends by longitudinal channels 18 for reception of the translucent panels 19. Connected to the upright bars 16, adjacent their forward edges, and in front of the panels 19, are parallel channels 20 for reception of the changeable silhouette letters 21, provided at their upper and lower edges with projecting lugs 22, which extend into the channels 45 20, the lugs being preferably flush with the rear face of the letters to bring the same into as close proximity to the panels 19 as possible. It will also be noted that the upper lugs 22 are of sufficient length to permit the letters 21 to be raised 50 55

until the lower lugs 22 clear the bottom channel 20 allowing the bottom of the letters to be swung outwardly and downwardly for removal from the top channel. Installation of the letters is accomplished by a reverse action, namely, first inserting the upper lugs 22 into the top channel, raising the letters and allowing the lower lugs to drop into the lower channel.

To releasably latch the hinged frame 11 in closed position, a spring clip 23 is secured to the wall 14 of the lower section 3 for reception of a catch 24 attached to the bottom channel 18 intermediate its ends, the lip 15 being cut out at 15' to allow passage of the catch. A thumb-piece 25, secured to the lower channel 18, facilitates manipulation of the frame.

From the foregoing explanation, considered in connection with the accompanying drawings, the purpose and operation of the invention will be readily apparent, in that any desired arrangement of silhouette letters may be positioned on the hinged frame 11 by insertion in the horizontal channels 20, and due to the opaque material from which the letters are formed, they will be clearly visible both at night, when the translucent panel 19 is illuminated, and in the daytime.

Access to the illuminating compartment 5 is easily and quickly obtained by merely swinging the frame 11 outwardly, thus facilitating replacement of the incandescent lights or illuminating elements when necessary. To remove the translucent panel 19 for either washing or replacement, the upper channel 18 is of sufficient depth to permit the panel to be raised sufficiently to clear the lower channel 18, after which it can be readily withdrawn from the upper channel. Obviously, this operation is performed when the hinged frame 11 is swung outwardly.

It will be noted that an exceedingly simple, rigid, and inexpensive structure has been provided, wherein the translucent panels and channel silhouette letters are both removably carried by a hinged frame, all of which facilitates three operations, namely access to the illuminating compartment, replacement or removal of the translucent panels for cleaning, and the interchanging and arrangement of letters.

Also, by the foregoing arrangement, the formation of the housing is materially simplified, in that the usual grooves provided for receiving the translucent panels and letter-supporting frames are eliminated. These grooves are further objectionable in that they form troughs within which rain, snow, and ice accumulate, causing subsequent prolonged dripping of the sign, whereas in the present structure rain or snow cannot accumulate, in that the lip 10, extending over the upper edge of the hinged frame and translucent panel carried thereby, forms a water shed, while the vertical lip 15, abutting the rear face of the lower channel 18, forms a closure at the bottom of the sign, and rain or snow contacting the outer face of the panel 19 and the letters 21 will readily drain off of the beveled edge of the lower section 3.

In the event of breakage of the translucent panels 19, the horizontal channels 20, as well as the changeable letters 21, will serve to retain the pieces and prevent their falling outwardly upon pedestrians.

While the invention has been illustrated in connection with a single translucent panel and

hinged frame, it is to be understood that any number of sections may be provided, depending upon the length of the sign.

I claim:

1. An illuminated sign comprising a housing having an open side, a longitudinal lip depending from the top of said housing adjacent said opening, an upwardly extending longitudinal stop on the bottom of said housing inwardly of said opening, electric illuminating means contained within said housing, a skeleton frame hinged to the top of said housing adjacent said opening for swinging outwardly, the top of said frame being normally positioned inwardly of said depending lip, and the bottom of said frame abutting said stop to form a closure for said opening and prevent accumulation of water in said housing, a translucent panel detachably carried by said frame, and silhouette letters detachably mounted in said frame in front of said panel. 20

2. An illuminated sign comprising a housing having an open side, electric illuminating means contained within said housing, a skeleton frame horizontally hinged to said housing adjacent its open side, said frame comprising spaced uprights connected at their upper and lower ends by horizontal channels, and a pair of spaced horizontal channels connected to said uprights intermediate their upper and lower ends, a translucent panel detachably mounted in said upper and lower channels rearwardly of said pair of horizontal channels, and silhouette letters detachably mounted in said intermediate horizontal channels. 30

3. An illuminated sign comprising a housing having an open side, electric illuminating means contained within said housing, a skeleton frame hinged to said housing adjacent its open side and adapted to swing outwardly and upwardly, a depending lip formed on the top of said housing 40 and extending over the face of said frame, a longitudinal stop formed on the bottom of said housing and abutting the inner lower edge of said frame, means for releasably latching said frame in normal closed position, a translucent panel detachably carried by said frame, and silhouette letters detachably mounted in said frame in front of said panel. 45

4. An illuminated sign comprising a housing having an open side, a longitudinal lip depending from the top of said housing adjacent said opening, an upwardly extending longitudinal stop on the bottom of said housing inwardly of said opening, electric illuminating means contained within said housing, a skeleton frame hinged to the top of said housing adjacent said opening for swinging outwardly and upwardly, the top of said frame being normally positioned inwardly of said depending lip, the bottom of said frame abutting the outer face of said stop, said frame comprising spaced uprights connected at their upper and lower ends by horizontal channels, a pair of spaced horizontal channels connected with said uprights intermediate their upper and lower ends, means for releasably latching said frame in normal closed position, a translucent panel detachably mounted in said upper and lower channels rearwardly of said intermediate channels, and silhouette letters detachably mounted in said intermediate horizontal channels. 65
